CLAIM

The ornamental design for a side element of a shoe upper, as shown and described.

DESCRIPTION

FIG. 1 is a side elevational view of a side element of a shoe upper showing my new design;

FIG. 2 is a front elevational view thereof; and,

FIG. 3 is a top plan view thereof.

The broken line showing of a shoe sole and the remaining portion of a shoe upper in FIGS. 1-3 is for illustrative purposes only and forms no part of the claimed design.
